[57] CLAIM

The ornamental design for a cap for container, as shown and described.

DESCRIPTION

FIG. 1 is a front perspective view of a cap for a container showing my new design;

FIG. 2 is a top plan view thereof;

FIG. 3 is a side plan view thereof;

FIG. 4 is a bottom plan view thereof; and,

FIG. 5 is the opposite side view thereof.

The surface shading in the drawing is intended to show that the container cap is transparent.
